UNITED STATES PATENT OFFICE.

ORWELL C. REEVES, OF TOLEDO, OHIO, ASSIGNOR TO TOLEDO SCALE COMPANY, OF
TOLEDO, OHIO, A CORPORATION OF NEW JERSEY.

PLATFORM CONSTRUCTION.

Application filed July 22, 1920. Serial No. 398,142.

To all whom it may concern:

Be it known that I, ORWELL C. REEVES, a citizen of the United States, residing at Toledo, in the county of Lucas and State of Ohio, have invented certain new and useful 5 Improvements in Platform Constructions, of which the following is a specification.

This invention relates to platforms of weighing scales and particularly to platforms employed in scales such as are used in 10 weighing comparatively heavy loads.

One of the principal objects of the invention is to provide a platform for scales of this type which has great strength and 15 rigidity but which is of comparatively light weight.

Another object is to so construct the platform as to give ready access to the pivots of the platform lever mechanism through openings which do not materially weaken the 20 construction.

Still another object is to provide a platform of this type which is of comparatively inexpensive construction and which is 25 adapted to be produced in quantities by modern factory methods.

Other objects and advantages will be apparent from the following description, in which reference is had to the accompanying 30 drawings illustrating a preferred embodiment of my invention and wherein similar reference numerals designate similar parts throughout the several views.

In the drawings:—

Figure 1 is a front view of a scale embodying my invention, the upper portion of the scale being broken away and my improved platform and other parts being shown in section, substantially on the line 1—1 of Figure 2;

Figure 2 is a side view showing substantially the same parts, the platform being in section approximately on the line 2—2 of Figure 3;

Figure 3 is a fragmentary plan view of the platform; and

Figure 4 is an enlarged perspective view of a hand-hole cover forming part of the platform.

The base of the scale, as well as the cabinet 2 or other supporting device for the load-offsetting mechanism, may be of any preferred construction, and is illustrated herein merely to show the relation of my improved 55 platform thereto. The platform levers may

also be of any preferred construction, those illustrated being fulcrumed upon bearing-supporting brackets 3 located adjacent the interior corners of the base 1, and having load pivots 4 which carry T-shaped supporting members 5.

Parallel links 6 depend from the cross-bar of each of the supporting members 5 and swingingly support the platform through connections to be hereinafter described.

The platform consists of a plate 7 of heavy sheet metal reinforced by channel bars 8 extending from front to rear adjacent the lateral edges of the plate and secured by riveting, spotwelding, or other suitable means, to its lower side, and channel bars 9 adjacent its front and rear edges similarly secured in place. Extending longitudinally of the plate 7 adjacent its center is a pair of angle bars 10 which are secured to the plate by riveting or otherwise and secured at their ends to the channel bars 9 by means of angle pieces 11.

The angle bars 10 form struts for truss rods 12 which lie beneath the bars 10 and are attached at their ends to brackets 13 secured to the lower side of the plate 7. The ends of the rods 12 pass through the brackets 13 and are provided with nuts 14 by means of which they may be drawn up.

Lying beneath the channel bars 8 and the angle bars 10 are narrower angle bars 15 which are secured to and further stiffen the plate 7. By means of the reinforcing channel and angle bars and truss rods I obtain a very strong, rigid platform structure with the use of comparatively light material. Secured to each of the transverse channel members 9 is a pair of bars 16 which extend across the channels of the longitudinal channel members 8 and pass respectively through the links 6, thereby supporting the platform structure. The edges of the channel members 8 are preferably notched to receive the supporting bars 16 so that the lower edges of the channel members 8 and 9 and the lower edges of the bars 16 are substantially flush. The outer ends of the supporting bars are fastened to the channel members 8 by means of vertical channel pieces 17.

In order to give access to the pivots at the corners of the base, as well as to the platform lever connection lying beneath the center of the platform, it has been customary heretofore to form a relatively large

opening in the center of the platform, the opening being normally closed by a plate set flush with the platform. In the platform of my invention I have avoided such 5 weakening of the structure as would be caused by cutting a large opening at the center, but have nevertheless made the corner and center pivots and connections readily accessible by providing relatively small 10 hand-holes at the corners and at the center of the platform. For each of the corner hand-holes there is a closure plate 18 such as is shown in Figure 4. As may be seen by inspection of Figure 3, each of the cover 15 plates 18 is adequately supported upon the channel bars 8 and 9, the angle bar 15 and the bracket 13. A hook 19 is secured to the lower side of each plate with its bill 20 extending beneath the edge of one of the channel members 8, and the plate is further secured in place by a screw 21 threaded into the angle bar 15. Each plate is also provided with a notch 22 of sufficient size to receive a screw-driver or similar instrument. 25 When the screw 21 has been removed, a screw-driver may be inserted into the notch 22 and the edge of the cover plate pried up. As the plate pivots upon its opposite edge, the hook 19 will swing away from the channel member 8 so that the cover plate may be lifted from its place.

The cover plate 25 at the center of the platform is supported upon the angle bars 10 held in place by screws 26.

35 While it will be apparent that the illustrated embodiment of my invention herein disclosed is well calculated to adequately fulfill the objects primarily stated, it is to be understood that the invention is susceptible 40 to variation, modification and change within the spirit and scope of the subjoined claims.

Having described my invention, I claim:

- 45 1. A scale platform comprising, in combination, a plate having downwardly-opening channel members secured to and extending along the lower face thereof, and link-supported cross bars bridging the openings in said channel bar.
- 50 2. In a weighing scale, in combination, platform levers, supporting members carried by said levers, links depending from said supporting members, a platform comprising a plate with downwardly-opening

channel members secured to and extending 55 along its lower face, said supporting members extending into the channels of said channel members, and bars bridging said channels and extending through said links.

3. In a scale platform, in combination, a 60 plate, angle bars secured to the lower face of said plate, truss rods passing under said angle bars and attached to said plate, and downwardly-opening channel members secured to the lower face of said plate adj- 65 cent its edges.

4. In a weighing scale, in combination, platform lever mechanism including a series of articulated parts, a platform supported upon said platform lever mechanism, said 70 platform comprising a plate, reinforcing members secured to the lower face of said plate, said plate having openings therein adjacent the articulated portions of said platform lever mechanism, said openings ex- 75 tending over certain of said reinforcing members, and cover plates in said openings resting on said reinforcing members.

5. In a weighing scale, in combination, platform lever mechanism comprising a 80 series of articulated parts, a platform resting upon said platform lever mechanism and comprising a plate, a reinforcing member secured to the lower face thereof, said plate having an opening adjacent one of the articulated portions of said platform lever mechanism, said opening extending over 85 said reinforcing member, and a cover plate for said opening having a hook extending beneath said reinforcing member. 90

6. In a weighing scale, in combination, lever mechanism comprising a series of articulated parts, a platform structure supported by said lever mechanism, said structure having an opening therein adjacent one 95 of the articulated portions of said lever mechanism and a closure for said opening comprising a plate, and a hook rigidly attached thereto and adapted when said closure is in closed position to extend beneath the portion of said structure and when said plate is tilted to be withdrawn from beneath said portion, and means for holding said plate against tilting. 100
